SOUND MUFFLING DEVICE

Ulrich Schmidt, Berlin-Wilmersdorf, Germany

Application April 25, 1935, Serial No. 18,083
In Germany December 17, 1932

6 Claims. (Cl. 181—48)

My invention relates to sound muffling devices, more particularly to devices for attenuating or silencing objectionable noise incident to the exhausts of internal combustion engines, intake 5 noises in motors, objectionable noise produced by fans, and other noise generating appliances.

The known type of sound muffler heretofore used in the art especially in connection with internal combustion engines for deadening the exhaust noise usually comprises a main channel or conduit passing the exhaust gases or other sound carrying medium and a sound deafening or acoustic absorbent material suitably associated therewith serving to attenuate or dissipate the 10 pressure or sound waves carried by the stream of gas or other medium.

According to one construction of a sound muffler heretofore known in the art, the acoustic absorbent material consisting for instance of glass wool and the like is so disposed within the 15 conduit passing the noise carrying gases, such as the exhaust gases in the case of an internal combustion engine, as to obstruct the flow of the gas or other sound carrying medium. According to a further construction as known in the art, the absorbent material is arranged contiguous to the 20 perforated main channel or conduit passing the exhaust gases or other sound carrying medium. All these constructions have the disadvantage 25 that due to the presence of foreign matter in the gas stream or other medium, such as soot or oil particles or other combustion residues in the case of internal combustion engines as combustion water, the interstices or pores of the sound 30 absorbent material become clogged or encrusted within a short period, thus greatly impairing the effectiveness of the muffling device or rendering the same completely ineffective after a comparatively short operating time. In order to somewhat 35 minimize this drawback, suggestions have been made to increase the effective sound dissipating surface or to sub-divide the gas current into separate units. This expedient, however, while not materially increasing the operating period before the absorbent material becomes 40 completely clogged and encrusted possesses the disadvantage of increasing the current resistance presented to the passage of the exhaust gases, thus in turn impairing the efficiency of the device 45 in connection with which the sound muffler is used, such as an internal combustion engine or the like.

In accordance with a further improvement, the acoustic absorbent material is disposed in such 50 a manner relative to the perforated main channel

or conduit passing the exhaust gases or other sound carrying material as to leave a free space in such a manner that the exhaust gases would not be allowed to come in direct contact with the sound attenuating or dissipating substance. 5 However, devices of this type have not been successful due to the presence of a difference in pressure between the points of ingress and egress of the exhaust gases passing through the main channel or conduit, whereby a major amount of 10 the gas current is shunted into the lateral or intermediary space, thus passing closely to the sound absorbing material and causing a clogging or encrusting in the same manner as in the previously described arrangements. In addition, 15 this construction has the disadvantage that only a limited amount of sound absorbing material may be provided, thus impairing the efficiency of the sound muffler as it is well known that the efficiency is proportional to the amount of absorbent material used. 20

Accordingly the object of my invention is to provide a sound muffler of the character described which is simple and easy in construction and highly efficient in silencing or attenuating undesired pressure or sound waves superimposed 25 upon a noise carrying medium such as the stream of exhaust gases in an internal combustion engine.

A further object of my invention is the provision of a sound muffling device in which the sound dissipating or attenuating material is disposed in such a manner as to be substantially free from interference by the sound carrying medium such as the exhaust gases in internal 30 combustion engines. 35

A further object of my invention is the provision of a sound muffling device for dissipating or attenuating objectionable sounds or noises carried by a moving medium such as the exhaust gases in an internal combustion engine whereby the acoustic absorbent material is acted upon by the sound waves to be dissipated only and is substantially free from interference by any foreign matter or additional constituents contained in 40 the sound carrying medium. 45

Another object of my invention is the provision of a selective sound muffler which is simple in construction and allows of an easy adjustment of the frequency or band of frequencies of the sound or pressure waves to be dissipated or attenuated. 50

Still a further object of my invention is the provision of a sound muffling device in the form of a sound filter which allows of an easy adjustment and design for dissipating or attenuat- 55

ing a band of predetermined width of objectionable sound waves or noises which it is desired to suppress.

The invention has other objects in view which will appear hereafter in the detailed description thereof in connection with the accompanying drawing in which I have shown a few exemplifications of a sound muffler specially adapted for suppressing the exhaust noise in internal combustion engines.

Figure 1 shows an elevation view with parts broken away of one form of embodiment of a sound muffler according to the invention.

Figure 2 shows a modified form of a muffler according to the invention; and

Figure 3 shows an embodiment of a sound muffler according to the invention for securing a filter effect for attenuating or dissipating a broad band of sound frequencies.

Similar reference numbers identify similar parts throughout the different views of the drawing.

With the above objects in view, my invention in general involves the provision in a sound muffling device of sound dampening or deadening surfaces offered by the acoustic absorbent material arranged in planes enclosing an angle, preferably a right angle with the direction of flow of the sound carrying medium or the main channel or conduit through which the sound carrying medium such as the exhaust gases of an internal combustion engine is passed. The invention is further differentiated from the prior art devices in that the acoustic absorbent material is arranged or packed in a chamber disposed laterally to and acoustically coupled with the main channel or conduit through which the sound carrying medium is passed in such a manner that the exhaust gas current or other sound carrying medium does not come in direct contact with the sound absorbing material, thus preventing any clogging or encrusting of the latter. The exhaust gases directly pass through the smooth main conduit while only the sound waves due to their tendency to radiate in all directions are absorbed by the noise deadening lateral chamber forming a reactive side branch or sound trap to use the analogy of wave traps in electrical circuits.

As is understood, in order to prevent the exhaust gases or other sound carrying medium from entering the sound absorbing chamber, no substantial "physical coupling" of the latter should exist with the main conduit with regard to the gas stream passing through the main conduit to use a further analogy of electrical circuits. In other words, no substantial pressure difference between separate points of the exhaust gas stream should be applied at separate ingress and egress points of the sound chamber which is likely to result in a substantial shunt or bypassing stream of the exhaust gas or other medium through the sound chamber and the absorbing material resulting in the drawbacks and disadvantages pointed out above. According to the present invention, this object is obtained by the provision of a closed imperforate sound absorbing chamber or chambers coupled substantially acoustically only with the main channel or conduit through which the sound carrying medium is passed in such a manner that only the sound or pressure variations carried by the latter are allowed to readily enter the lateral absorbing chamber, which latter is substantially

"physically decoupled" from the main channel or conduit with regard to the stream of the exhaust gases or other medium passed therethrough. In the example illustrated, the latter object and effect is secured by the provision of a single narrow connecting path between the main conduit and an absorbing chamber sufficient to provide efficient acoustic coupling for the pressure variations of a predetermined frequency range to be eliminated, but insufficient to apply substantial pressure difference to the side chamber likely to result in a by-passing or shunting of sound carrying medium through the side chamber.

Extensive experiments have proven that a sound muffler according to the invention possesses a considerably higher efficiency as compared with sound mufflers heretofore known while at the same time presenting the advantage that the sound deadening material is free from becoming clogged or encrusted or otherwise being interfered with by the exhaust gases or other sound carrying medium and consequently from losing its acoustic or sound deafening effectiveness. In addition, the efficiency of the device may be further increased by an increase of the effective dissipating or sound dampening surface of the absorbent material by the use of a desired number of serially arranged lateral chambers or reactive side branches each disposed in shunt relationship to the main channel or conduit carrying the exhaust gases or other noise carrying medium.

Referring more particularly to Figure 1 of the drawing illustrating a simple form of embodiment of a sound muffler especially adapted for use in connection with internal combustion engines, I have shown at 1 a main duct or channel through which the exhaust gases or other sound carrying medium is passed. The channel 1 has an opening 2 connecting it with a closed laterally disposed tubular shaped chamber 3. Item 4 represents a foraminous or perforated tube leading from the opening 2 into the lateral chamber 3 as shown. The space between the tube 4 and the outer walls of the chamber 3 is packed with acoustic absorbent material shown at 5.

In a device of this type, as is understood, the exhaust gases passing through the tube 4 are prevented from coming in contact with the absorbent material 5, thus avoiding any clogging or encrusting of the latter and consequent impairment of the effectiveness of the muffling device. Only the sound waves will pass through the opening 2 into the chamber 3 due to their tendency to radiate in all directions and to produce noise which is to be suppressed by the muffler. The sound waves entering into the chamber 3 through the foraminous tube 4 are spread over the openings of the latter and impinged upon the absorbing material 5 in such a manner as to become attenuated or dissipated in a known manner. Since the exhaust current does not come in contact with the tube 4, the latter may have a large surface and may be roughened to a desired degree without increasing the resistance against the flow of the exhaust gases. In addition, as will be understood, the chamber 3 may possess any desired shape to suit special requirements such as lack of space without making it necessary to pay any consideration to the current conditions of the exhaust gases.

Furthermore, any desired number of chambers 3 of desired construction may be provided, such as for instance three tubular chambers of the type described arranged next to each other upon the

main conduit 1 and extending radially from the latter.

Referring to Figure 2, this shows a modified construction of a sound muffler according to the invention in which the lateral chamber encloses an annular space 6 disposed around the main conduit 1. In this case the total sound dampening effect may be increased by using a plurality of chambers 6 arranged around the main conduit 1. In a construction of this type the main conduit 1 is interrupted for a length equal to the free annular space 7, thus allowing the sound waves at this point to radiate freely and in all directions into the annular space 7 while the gas current is passed through the conduit 1 without entering the annular side chamber. The latter is bounded by two wire sieves or foraminous metal sheets or discs as shown at 8 and the sound absorbent material 5 packed therebetween, as shown, and the outer walls of the chamber 8.

Since the shape of the chambers 3 or 6 in which the sound is damped or deadened does not in any way interfere with the exhaust current in the main conduit 1, a device of the type according to the invention lends itself in an easy and simple manner to the construction of an acoustic filter by the use of a plurality of chambers or reactive side branches 3 and 6 of suitable diameter and length and properly spaced from each other. The acoustic filter functions in that those frequencies, such as the low notes not affected by the damping material by reason of the unitary construction of the lateral chambers will be filtered and deadened by the subsequent chambers.

Referring to Figure 3, this shows one embodiment of an acoustic filter according to the invention comprising five chambers or reactive side branches 10 to 14 arranged in succession and constructed or tuned to be effective in suppressing a series of separate frequencies whereby each of these chambers will have a different selective effect in dampening or dissipating the sound waves. In the embodiment shown, the first chamber 10 is constructed in the form of a pure absorption chamber in such a manner that the cross section 15 of the sound channel enclosed by the sound dampening material 5 corresponds to the cross section 16 of the coupling opening for the sound waves entering into the chamber 10. The next chamber 11 is designed in such a manner that the space enclosed by the open annular chamber 17 on the one hand is larger than the space of the chamber 10, and on the other hand that the opening cross section 18 for the sound waves from the main conduit 1 into the chamber 11 is less than the open cross section 17 of the latter. The relationship of the volume of the annular chamber 11 to the opening cross section may be given such a value that this arrangement by its filter action becomes effective in suppressing a predetermined low frequency band. The next chamber 12 differs from the chamber 11 merely by the sub-division of the opening cross section into several units 19 whereby the acoustic filter effect may be modified as compared to the chamber 11. The construction of the next following chamber 13 is such that the glass wool or other absorbent material 5 forms a pair of discs 20 bounded by the perforated or foraminous sheets 8 and 8' and disposed at a predetermined distance from the walls of the chamber 21. In an arrangement of this nature the sound waves penetrate the glass wool or other absorbent material 5 in such a manner as to enter freely into the space 22 behind the absorbent material 5 to be impinged upon the walls

of the chamber 21, and reflected back against the glass wool or other absorbent material 5. This, as will be understood, results in an increased dampening or dissipating effect and the attainment of a definite selectivity determined by the distance 5 between the dampening surfaces from the walls of the chamber 21. The last chamber 14 is a modification of the chamber 13 whereby in order to prevent standing waves in the air space 23 the entire chamber 14 with the exception of the 10 annular slot bounded by the coupling opening 24 is packed with acoustic absorbent material in a manner similar to the first chamber 10.

The separate chambers 10 to 14 may be designed individually in accordance with the constructions shown by Figures 1 and 2 or they may form a unitary structure as shown in Figure 3. In the latter, the walls of one chamber form the boundary for the next following chamber whereby the entire structure forms a simple 20 compact unit. In place of the perforated sheets 8, wire sieves or the like means may be provided for allowing the passage of the sound waves, and tubular chambers as shown in Figure 1 may be substituted for the annular chambers illustrated 25 in Figure 3, as will be readily understood.

As is obvious from the above, a sound muffling device according to the invention has many additional uses for suppressing or silencing objectionable noises such as the intake noise in motors, 30 noise produced by fans, firearms, etc. and in general appliances operating with a noise producing moving medium.

While I have shown the invention embodied in the specific constructions exemplified in the 35 drawing, it will be obvious that the same is susceptible of various modifications and variations coming within its broader spirit and scope as expressed by the ensuing claims.

I claim:

1. A sound muffler comprising a conduit providing a substantially unobstructed gas flow and having a circular opening, a closed imperforate annular chamber surrounding said conduit, a plurality of perforated partition walls arranged substantially transversely to said conduit and dividing said chamber into a number of adjacent compartments, and packings of sound absorbing material filling alternate compartments, the central non-filled compartment having a width equal 50 to said opening and communicating therethrough with said conduit to provide an acoustic coupling path therebetween and said conduit.

2. A sound muffler comprising a conduit providing a substantially unobstructed gas flow, a 55 plurality of side chambers coupled to said conduit acoustically only so as not to form part of the path traversed by the gas, and packings of sound absorbing material filling a part of said side chambers and presenting absorbing surfaces 60 therein substantially transverse to the gas flow through said conduit.

3. A sound muffler comprising a conduit providing a substantially unobstructed gas flow, a 65 plurality of contiguous side chambers concentrically surrounding said conduit, foraminous partition walls arranged substantially transverse to the gas flow through said conduit and dividing each of said chambers into two compartments, one compartment of each of said chambers communicating with said conduit through annular openings therein adapted to provide 70 acoustic coupling paths but forming no part of the path traversed by the gas, and packings of 75

sound absorbing material filling the other compartments of each of said side chambers.

4. A sound muffler as claimed in claim 2 in which said side chambers are of different size so that each is effective in dissipating sounds of a different frequency range.

5. A sound muffler comprising a conduit providing a substantially unobstructed gas flow and having an opening therein, a closed imperforate 10 annular chamber surrounding said conduit, and a plurality of perforated partition walls arranged transverse to said conduit and dividing said chamber into a number of adjoining compartments, packings of sound absorbing material fill-

ing alternate compartments, at least one of the non-filled compartments being acoustically coupled to said conduit through said opening.

6. A sound muffler comprising a conduit providing a substantially unobstructed gas flow and having a plurality of spaced openings therein, a side chamber communicating with said conduit through said openings, and a packing of sound absorbing material filling a part of said side chamber laterally of said openings and presenting an absorbing surface therein substantially transverse to the gas flow through said conduit. 10

ULRICH SCHMIDT.
